The ornamental design for an instrument panel for an automobile, as shown and described.

(30) **Foreign Application Priority Data**

DESCRIPTION

Aug. 28, 2015 (JP) 2015-019055

FIG. 1 is a front elevational view of an instrument panel for an automobile in accordance with our new design;

(51) **LOC (10) Cl.** **12-16**

FIG. 2 is a top plan view thereof;

(52) **U.S. Cl.**

FIG. 3 is a bottom plan view thereof;

USPC **D12/192**

FIG. 4 is a right side elevational view thereof;

(58) **Field of Classification Search**

FIG. 5 is a left side elevational view thereof;

USPC D12/400, 414, 415, 416, 417, 418, 419,

FIG. 6 is a front, left side perspective view thereof; and,

D12/420, 421, 422, 424, 425, 426, 190,

FIG. 7 is a front, right perspective view thereof.

D12/192, 162, 195, 191, 106, 345, 96, 99

A second embodiment of our new design is identical to the first embodiment. The second embodiment of our new design includes the mirror image of the instrument panel shown in FIGS. 1 to 7.

CPC B60R 7/04; B60R 7/08

The rear view and rear surfaces of the instrument panel form no part of the claimed design. The instrument panel is configured to be mounted to an automobile. The inside surfaces of the instrument panel, shown in broken lines in FIGS. 2 to 5, form no part of the claimed design since the inside surfaces are hidden when the instrument panel is mounted to the automobile.
